CLAIM

The ornamental design for a skin treatment attachment, as shown and described.

DESCRIPTION

The patent or application file contains drawings executed in color. Copies of this patent or patent application publication with color drawings will be provided by the Office upon request and payment of the necessary fee.

FIG. 1 is a perspective view of a skin treatment attachment; FIG. 2 is a front view thereof;

FIG. 3 is a right side view thereof;

FIG. 4 is a rear view thereof;

FIG. 5 is a left side view thereof;

FIG. 6 is a top plan view thereof.

FIG. 7 is a perspective view of a second embodiment of a skin treatment attachment;

FIG. 8 is a front view thereof;

FIG. 9 is a right side view thereof;

FIG. 10 is a rear view thereof;

FIG. 11 is a left side view thereof; and,

FIG. 12 is a top plan view thereof.

Color drawings are being submitted because color is an integral part of some embodiments of the claim design.
